UNITED STATES PATENT OFFICE.

GEORGE COLLARD, OF SLOUGH, ENGLAND, ASSIGNOR OF ONE-FIFTH TO
ARTHUR GLADWELL, OF SLOUGH, ENGLAND.

FLASH-LAMP.

SPECIFICATION forming part of Letters Patent No. 699,452, dated May 6, 1902.

Application filed September 16, 1901. Serial No. 76,589. (No model.)

To all whom it may concern:

Be it known that I, GEORGE COLLARD, of Tylney Villa, Wellington street, Slough, in the county of Buckingham, England, have 5 invented a Flash-Lamp to be Used for Photographic and other Purposes, such as Producing Stage Effects; and I do hereby declare the following to be a full, clear, and exact description of the invention, such as will enable 10 others skilled in the art to which it appertains to make and use the same.

The device consists of a construction whereby a charge of finely-divided material which is quick burning and which possesses intense 15 illuminating power may with great velocity be suddenly ejected through the flame of a spirit-lamp into the air from an elongated narrow tray which is first impelled by the force of constrained springs which are released by a trigger at the will of the operator 20 and then suddenly stopped, whereby a sheet of flame is produced which emits a momentarily brilliant light.

The annexed drawings, which form a portion 25 of my specification, show the exact shape and detail of the apparatus by which, as far as I at present know, the operations which I have described may be most effectively performed.

30 Figure 1 is a front sectional elevation taken through the center of the apparatus, showing the tray in the raised position in which it would be situated for the purpose of charging it with the inflammable powder and 35 also its position at the instant it is suddenly stopped. Fig. 2 is an end sectional elevation taken through the center of the length, showing the apparatus ready for firing. Fig. 3 is a front elevation of the portion consisting of 40 the tray, the headpiece to which the tray is fastened, (this being in section,) and the stop bolts and nuts. Fig. 4 is a plan of the tray. Fig. 5 is an oblique view of the spring loop and trigger. Fig. 6 is a transverse section 45 showing a modification in the construction of the tray to provide for the succession of flashes.

In the figures, T is a long narrow tray shown charged with magnesium powder, which is 50 distributed uniformly along its length. The tray is fastened by screws to a sliding head-

piece H, which is capable of movement in a vertical direction, being guided by the sides of the ejector E. At a lower level a floor-piece F is secured to the sides of the ejector 55 E. Interposed between these two pieces H and F are two helical springs S' and S², which, resting on the fixed floor F, tend to force the sliding head H and the tray above it upward. The upward movement is limited by the use 60 of two stop-bolts B' and B². The bolts are threaded through holes bored opposite one another in both H and F and are screwed into nuts N' and N², which are sunk in recesses 65 provided in the upper side of H, the recesses fitting the nuts and preventing them from turning. The heads of the bolts are underneath the floor F, leather washers being interposed to deaden the noise of the blow which would be produced if they came in 70 contact. The bolts are also passed through the helical springs S' S² and thus serve to retain them in place.

The headpiece H and tray are detained in the lower position shown in Fig. 2, the springs 75 being then compressed by means of the hook K, which is secured to the sliding head H, and the loop L, which is secured to the base of the ejecting apparatus. The loop is made of spring-steel wire which before tempering 80 is bent to the form shown in the figures. The oblique view shown in Fig. 5 shows the form most clearly. The shape adopted facilitates the attachment of the wire to the base of the apparatus by a plate P and screws in such a 85 way that the resilience of the wire will tend to cause the loop to move to the right in Fig. 2 and hitch itself onto the hook K when the latter is forced downward sufficiently far. Also the ends of the wire being inserted into 90 small holes in the trigger-plate J the movement to the right is limited, and the loop is held in such a position as to be ready to slip over the hook when it is forced down.

The trigger-plate J is pivoted at J', and on 95 being pulled by a string attached to J² it is moved into the dotted position and pulls the loop L from the hook K, which is thereby released.

Entirely around the periphery of the orifice 100 at the top of the ejecting apparatus a narrow chamber or recess R is provided, of width just

sufficient to hold a wick W, there being also a passage Q leading around the wick from two supply-tubes C' and C². In this way the wick, which entirely surrounds the opening 5 through which the magnesium powder is ejected, can be saturated with spirit. The lower edge of the wick is bound with a narrow strip of thin metal bent around it, the spring of which retains the wick securely in 10 place. When lighted, the flames from the wick on the two sides of the orifice will be drawn together on account of the air-supply being only on the outside, and thus a mantle of flame will completely cover the orifice 15 of discharge.

To facilitate the production of a succession of flashes without the necessity of recharging each time, the tray may be constructed with one or more shelves, as shown in Fig. 6, 20 each carrying a layer of the magnesium powder. It will be from the uppermost shelf only that the powder will be ejected. When that has been discharged, the top shelf may be withdrawn through a slit at the end, expos- 25 ing the next layer, and so on.

To use the apparatus, the tray T is first charged with the magnesium powder, and then the springs are compressed by applying sufficient force to the two handles Y' and Y² to 30 push down the sliding head H until the loop L slips over the hook K and detains it. The wick having been saturated with spirit is then lighted, and the apparatus is ready for firing. On pulling the trigger at J² the hook 35 K will be released and permit the springs S' and S² to force the tray T upward with increasing velocity until it is suddenly arrested by the heads of the bolts B' and B² coming in contact with the under surface of the floor- 40 piece F. The magnesium powder lying loose in the tray having acquired a considerable velocity will continue its motion upward and be ejected through the mantle of pale flame which covers the orifice and be ignited and 45 produce a sheet of flame of intense brilliance. After the flash the flame of the wick may be extinguished by a cover.

It is not essential to the successful working of my invention to follow the construction I have described in every detail. For instance, 50 the piece to which the tray is attached or the tray itself may be hinged at one end and be compelled to swing forcibly against a stop and so jerk the powder into the air.

What I claim, and desire to secure by Letters Patent, is—

1. A flash-lamp comprising a narrow elongated tray, an ejector-casing in which said tray is moved, vertically, springs within said casing for moving the tray upward in said 60 casing, a trigger mechanism for holding the tray with the springs compressed at a point considerably within the casing and stops or abutments for limiting the outward movement of the tray, said casing having at its upper end about its elongated mouth a narrow channel extending about it for a wick and for receiving a combustible fluid, substantially 65 as described.

2. A flash-lamp comprising a narrow elongated tray, an ejector-casing in which said tray is moved vertically, springs within said casing for moving the tray upward in said 70 casing, a trigger mechanism for holding the tray with the springs compressed at a point 75 considerably within the casing and stops or abutments for limiting the outward movement of the tray, said casing having at its upper end about its elongated mouth a narrow channel extending about it for a wick and for 80 receiving a combustible fluid, said stops comprising bolts connected with the tray and disposed at different points along the same, and a floor against which the bolt-heads strike, 85 said trigger mechanism being arranged substantially centrally of the tray, substantially as described.

In witness whereof I hereunto set my hand in the presence of two witnesses.

GEORGE COLLARD.
